UNITED STATES PATENT OFFICE.

CHARLES BRUCE GARDNER, OF STAFFORD, ENGLAND.

APPARATUS FOR CLEANING THE FIRE TUBES OF MULTITUBULAR BOILERS AND THE LIKE.

Application filed April 8, 1927, Serial No. 182,114, and in Great Britain March 10, 1926.

This invention relates to that class of apparatus particularly adapted for cleaning the fire tubes of a multi-tubular boiler, although applicable also for use with air heaters and some forms of feed water heaters, which apparatus is characterized by single nozzles or discharge openings corresponding in number to the fire or equivalent tubes to be cleaned, and arranged coaxially there-
5 with, by which means all the tubes can be treated without anything more than establishing the supply of blowing fluid.

Ordinarily with apparatus of this particu-
10 lar class, the flow of hot gases to the fire tubes is unduly interfered with if an ade-
quate flow of blowing fluid is provided and the object of the invention, which is to over-
come this disadvantage, is achieved by em-
ploying blow-pipes from which the nozzles
20 extend, arranged in two rows and relatively
staggered, at distances sufficient to provide
space for the ready flow of hot gases to or
from the boiler tubes.

In order to keep the amount of fluid un-
25 der pressure being used at any time within
moderate limits, and also so as not unduly
to interfere in a boiler, with the heating of
the boiler by hot gases passing through its
fire tubes, the nozzles corresponding to the
30 fire tubes are divided up into separate groups
to which fluid under pressure can be sup-
plied in succession through two or more con-
duits provided with controlling means, so
that groups of fire tubes opposite the groups
35 of nozzles can be cleaned in succession.

The tube cleaning apparatus is arranged
in position with regard to one end of the
tubes to assure its being in exact position
with the nozzles properly disposed in rela-
40 tion to the ends of the boiler tubes.

Apparatus according to the invention can
be variously constructed, as will be under-
stood from the further description of the in-
vention now about to be given with the aid
45 of the accompanying drawings wherein Figs.
1 and 2 are sectional elevations of one form
or arrangement of heating plant or boiler
taken at right angles to each other, only a
few of the blow-pipes being represented; and
50 Fig. 3 is a plan view thereof.

Referring to the drawings, 1 denotes the
nozzles which are preferably equal in num-
ber to the boiler tubes 2 and which, as in the
arrangement shown in the drawings, may be
55 short and carried by blow-pipes 4 fixed to the

side or bottom of a box or header 3, so that
fluid under pressure can flow through all
the nozzles simultaneously. In the present
instance, the box or header 3 is shown in two
sections divided into chambers 3^a, each pro-
vided with a valve controlled fluid inlet pipe
such as 5, so that the nozzles, or blow-pipes
and nozzles may be divided off or separated
into groups to which fluid under pressure
can be supplied in succession. In Fig. 2,
60 valves 4^a are shown fitted to each of the
pipes 4 whereby admission of fluid to each
vertical line of blowing nozzles 1 can be
controlled toward and from the tubes by
making appropriate constructional modifica-
65 tions. The nozzles 1 carried by blow-pipes
4 are so designed as to prevent their undue
interference with the flow of hot gases to the
fire tubes and for such purpose said blow-
pipes are arranged in two rows relatively
70 staggered, those further from the boiler
tubes being provided with longer nozzles
than the others, so that the exit ends of all
the nozzles shall terminate in the same plane.
If preferred, all of the blow-pipes may be
75 provided with relatively long nozzles of
somewhat smaller cross-section than repre-
sented.

In Fig. 1 some of the blow-pipes 4 have
80 been omitted for the purpose of clearer dis-
closure, but the number of such pipes is in-
tended to be equal to the number of vertical
rows of fire tubes, less the two outermost
rows, each blow-pipe being provided with a
85 series of nozzles 1 equal in number to the
number of fire tubes in each row thereof ex-
cept the outermost pair of blow pipes, which
in this instance are provided with additional
nozzles 1^a for dealing with the rows of fire
90 tubes for which no blow pipes are provided.
These blow-pipes 4 are shown depending
from a header 3 shown in sections, the lat-
ter being supported outside the chamber 6 in
which the blow-pipes with the nozzles are
95 arranged for use. When arranged in groups
in different parallel vertical planes, these
blow-pipes may be connected to different
headers, or to separate chambers 3^a in the
same header (see Figs. 2 and 3). Fluid un-
100 der pressure may be supplied to all the blow-
pipes and nozzles simultaneously, or to
groups thereof in turn. Further, the head-
er or headers with described pipes and noz-
zles may be made removable from the boiler
105 when not required for use.

The apparatus may be placed either at the inlet or outlet end of the boiler tubes. When the temperature of the gases entering the boiler tubes is sufficiently low, it is generally preferable to arrange the apparatus at the inlet end of the boiler tubes, but where the temperature is so high that it would cause injury to the apparatus or to parts hereof, it is preferable to arrange the apparatus at the outlet end of the boiler tubes. In the latter case, if the pressure of the cleaning fluid at the nozzles is sufficiently high, the jets of fluid will clean the boiler tubes, or groups of tubes against the draught of the boiler, which in the meantime, may or may not be temporarily reduced or stopped.

What I claim is:—

1. An apparatus of the class described, comprising a horizontal header having a fluid inlet, a series of blow pipes depending from the header in two rows, the pipes in one row being staggered in relation to the pipes of the other row, and a series of nozzles projecting horizontally from each blow pipe, the nozzles of one row of pipes being longer than the nozzles of the other row of pipes and extending between the pipes of the last mentioned row, with all the nozzles terminating in a common plane.
2. An apparatus of the class described, comprising a horizontal header having a fluid inlet, a series of blow pipes depending from the header in two rows, the pipes in one row being staggered in relation to the pipes of the other row, a series of nozzles projecting horizontally from each blow pipe, the nozzles of one row of pipes being longer

than the nozzles of the other row of pipes and extending between the pipes of the last mentioned row, with all the nozzles terminating in a common plane, and a series of valves in said header, each of said valves being adapted to control a blow pipe.

3. An apparatus of the class described, comprising in combination with a nest of tubes, a horizontal header having a fluid inlet, a series of blow pipes depending from the header in two rows with the pipes in one row staggered in relation to the pipes in the other row, a series of nozzles projecting horizontally from each blow pipe, the nozzles of the pipes in one row being longer than the nozzles of the pipes in the other row and extended between the pipes of the last mentioned row so that all the nozzles terminate in a common plane, said nozzles being coaxial with the tubes of the nest of tubes, and a series of valves in said header, each of said valves being adapted to control a blow pipe.

4. An apparatus of the class described, comprising in combination with a nest of tubes, a chamber with which said tubes communicate, a horizontal header having a fluid inlet, a series of cleaning fluid pipes connected with and depending from the header into said chamber adjacent said tube ends in two rows with the pipes in one row staggered in relation to the pipes in the other row, and a series of nozzles projecting horizontally from each blow pipe in coaxial alignment with the tubes of the nest.

Signed at Stoke-on-Trent, England, this twenty-second day of March, 1927.

CHARLES BRUCE GARDNER.
